Application March 29, 1947, Serial No. 138,042

Term of patent 14 years

(Cl. D91—1)

To all whom it may concern:

Be it known that I, Charles Stowe Myers, a citizen of the United States and residing at Altadena, in the county of Los Angeles, State of California, have invented a new, original, and ornamental Design for a Water Softener Valve Housing, of which the following is a specification, reference being had to the accompanying drawing, forming part thereof, in which:

Fig. 1 is a view in front elevation of a water softener valve housing, showing my new design;

Fig. 2 is a view in side elevation as taken from the left of Fig. 1;

Fig. 3 is a view in side elevation as seen from the right of Fig. 1;

Fig. 4 is a top plan view and

Fig. 5 is a bottom plan view thereof.

The back of the article is substantially plain.

I claim:

The ornamental design for a water softener valve housing, substantially as shown and described.

CHARLES STOWE MYERS.
